FILING DRAWER OR THE LIKE

Walter F. Regenhardt, Cleveland, Ohio

Application June 19, 1935, Serial No. 27,283

7 Claims. (Cl. 129—31)

The present invention relates to filing drawers or the like and more particularly to filing drawers employing a follower file-back.

One of the objects of the present invention is to provide for the quick release of the follower filing-back so that it can be slid horizontally within the drawer and to insure a binding relation between the back and the drawer wall accomplished by the manipulation of the file-back 10 itself.

Another object of the invention is to provide a plurality of abutments on the drawer to be engaged by members on the file-back to limit the movement of these members and thereby limiting 15 the rearward movement of the file-back and which members are released from their binding relation with the abutments by merely pulling forwardly on the upper part of the file-back.

A further object of the present invention is to 20 pivotally attach a plurality of camming members on the file-back which members are adapted to cam themselves into binding relation with abutments in the file drawer when force is exerted rearwardly at the upper part of the file-back and 25 which are arranged to release this binding relation by merely pulling forwardly on the upper part of the file-back.

Further objections and advantages will be apparent from the following disclosure, reference 30 being had to the accompanying drawing wherein a preferred form of embodiment of the present invention is clearly shown:

In the drawing:

Fig. 1 is a longitudinal sectional view taken on 35 line 1—1 of Fig. 3 and also shows part of one of the guides broken away.

Fig. 2 is a fragmentary view similar to Fig. 1 but showing the follower file-back in a different position; and

Fig. 3 is a sectional view taken on line 3—3 of 40 Fig. 1.

Referring to the drawing, and for the purpose of illustrating the application of the present invention in connection with a filing drawer for file 45 cabinets, there is shown a drawer 20. The opposite sides 21 and 22 and the bottom 23 of the drawer are preferably formed of sheet metal. A front 25 is suitably attached to the sides and bottom walls and is provided with a pull 26. From the point 27 and rearwardly thereof the upper edges of the sides 21 and 22 are bent inwardly to form abutments 28 and then downwardly as at 29 to provide open bottom horizontal 50 extending guides at the upper ends of the side walls.

The follower file-back 31 is also preferably formed of sheet metal and the lower part 32 is bent back on itself to form the slot 33 and is attached at 34 to the main body of the back 31 by spot welding or by rivets 36. For the purpose 5 of providing a facile manner of releasably holding the follower file-back in position, I provide members on the file-back which are arranged to impinge with the abutments 28 and the bottom wall 23 of the drawer 20. The bottom wall functions as an abutment for the members. These members include a U-shaped camming member 37 having legs 38 and 39 and a connecting yoke 40. The yoke 40 is arranged to slide on the bottom 10 23 of drawer 20 and the legs 38 and 39 slide along 15 the side walls 21 and 22 of the drawer 20. The entire upper edges of legs 38 and 39 are inclined rearwardly to form camming surfaces 42. The file-back 31 is carried between the legs 38 and 39 and is pivotally connected to these legs by a roller 20 43 and a pin or shaft 44. The shaft 44 extends through the roller 43 and the opposite ends thereof are journaled in the legs 38 and 39. The roller 43 is disposed within the slot 33. Camming members 46 and 47 are arranged along the inner opposite sides 21 and 22 of the drawer 20 and extend into the guides formed by the downwardly extending portions 29 of the sides 21 and 22. The lower edges of the cam members 46 and 47 are inclined to form camming surfaces 48 which correspond in an angular inclination with the camming surfaces 42 of the U-shaped camming members 37. A roller 50 is disposed in the upper part 25 of slot 33 and receives a pin 51 which in turn has its opposite ends journaled to the cam members 35 46 and 47.

Fig. 1 of the drawing shows the follower file-back in its file holding position. When the upper part of the file-back 31 is moved forwardly, as shown in Fig. 2, the camming members 46 and 47 will be moved forwardly because of the interconnection of said file-back and members 46 and 47 through the roller 50 and pin 51. The camming members 46 and 47 will then slide downwardly on the camming surfaces 42 to release 45 the binding relation between the camming members 46, 47, yoke member 40 and the abutments 28 and 23; it being understood that bottom wall 23 of the drawer 20 forms an abutment for the camming member 37. When this binding relationship is released, the file-back 31 and the camming members 37, 46 and 47 can be slid horizontally 50 on the bottom wall 23. When it is desired to fasten the file-back in position, it is necessary only to rotate the upper part of the file-back in 55

a rearwardly direction. This will cause the camming surfaces 48 to slide upwardly on camming surfaces 42 whereby the camming members 46 and 47 will engage the top abutments 28 and then 5 by exerting a little more force in the same direction, the camming member 37 will be impinged tightly against the bottom wall 23 of the drawer.

If no front is provided, the file-back 31 and camming members 37, 46 and 47 can be inserted 10 from the front as an assembly, or, this assembly can be inserted from the rear. However in the present embodiment wherein a front is provided for the cover and the rear is folded in as at 53, the assembly is inserted into the drawer from 15 the top, and to accomplish this, the guides 29 stop at 21 so that the assembly can be inserted forward of this point.

From the foregoing, it will be seen that it is necessary only to rotate the file-back itself in a 20 forward direction in order to release the same for sliding movement in the drawer and in order to hold the file-back in a desired position, it is necessary to rotate the file-back itself in a rearwardly direction.

25 What I claim is:

1. A filing drawer comprising in combination, sheet metal providing side walls and a connecting bottom wall, the upper edges of the side walls being bent inwardly and downwardly to form 30 horizontally extending guides and abutments, a member slidable in each of said guides, said members each having a camming surface on the lower edge thereof, means slidable over the bottom wall and providing spaced camming members 35 each having a camming surface on the upper edge thereof adapted to cooperate with the first mentioned camming surfaces, and a follower file-back pivotally attached to all of said members and adapted, when rotated rearwardly, to cause the camming surfaces to cam the sliding members into binding relation with the abutments and bottom wall, respectively.

2. A filing drawer comprising in combination, side walls and a connecting bottom wall, said side 45 walls each having a horizontally disposed abutment, a U-shaped camming member, the yoke of said member being slidable on the bottom wall and the upper edges of the legs of the member being inclined to form camming surfaces, a follower file-back pivotally attached to the member and slidable therewith, a pair of cams each having a lower camming surface and spaced from one another for cooperation with the camming surfaces of the U-shaped camming member, said 55 cams being carried by the file-back and adapted to cam the U-shaped member downwardly into binding relation with the bottom wall and cam the cams upwardly into binding relation with the abutments when the file-back is rotated rearwardly.

3. A filing drawer comprising in combination, side walls and a connecting bottom wall, said side 65 walls each having a horizontally disposed abutment, a U-shaped camming member, the yoke of said member being slidable on the bottom wall and the upper edges of the legs of the member being inclined to form camming surfaces, a follower file-back pivotally attached to the member and slidable therewith, a pair of cams each having a lower camming surface and spaced from one another for cooperation with the camming surfaces of the U-shaped camming member, said 70 cams being pivotally carried by the file-back and adapted to cam the U-shaped member downwardly into binding relation with the bottom wall and cam the cams upwardly into binding relation with the abutments when the file-back is rotated rearwardly.

wall and cam the cams upwardly into binding relation with the abutments when the file-back is rotated rearwardly.

4. A filing drawer comprising in combination, sheet metal providing side walls and a connecting bottom wall, the upper edges of the side walls being bent inwardly and downwardly to form horizontally extending guides and abutments, a member slidable in each of said guides, said members each having a camming surface on the lower edge thereof, a U-shaped camming member, the yoke of said U-shaped member being slidable on the bottom wall and the upper edges of the legs of the U-shaped member being inclined to form camming surfaces cooperable with the first mentioned camming surfaces, and a follower file-back pivotally attached to all of said members and adapted, when rotated rearwardly, to cause the camming surfaces to cam the sliding members into binding relation with the abutments and bottom wall, respectively.

5. A filing drawer comprising in combination, side walls and a connecting bottom wall, the side walls each having a horizontally extending abutment, a follower file-back disposed between the 25 side walls and transversely thereof, an element slidable on the bottom wall and having members extending upwardly at opposite side edges of the file-back and each having a camming surface on the upper edge thereof, means for pivotally attaching said members to the file-back, other slidable members vertically aligned with the first mentioned members and arranged to engage said abutments and each having a camming surface on the lower edge thereof for cooperation with the first mentioned camming surfaces, and means for pivotally attaching said other slidable members to the file-back, one of said attaching means being translatable movable with respect to the file-back.

6. A filing drawer comprising in combination, side walls and a connecting bottom wall, the upper side walls each having a horizontally extending abutment; a follower file-back disposed between the side walls and transversely thereof, 45 said file-back having a horizontal slot extended completely across the same; an element slidable on the bottom wall and having members extending upwardly at opposite side edges of the file-back and each having a camming surface on the upper edge thereof; means for pivotally attaching said members to the file-back; other slidable members vertically aligned with the first mentioned members and arranged to engage said abutments and each having a camming surface 50 on the lower edge thereof for cooperation with the first mentioned camming surfaces; and means for pivotally attaching said other slidable members to the file-back, one of said attaching means including a horizontal pivot pin 55 for certain of said members, said pin extending through the slot and projecting on opposite sides of the vertical side edges of the file-back.

7. A filing drawer comprising in combination, side walls and a connecting bottom wall, the side 65 walls each having a horizontally extending abutment; a follower file-back disposed between the side walls and transversely thereof, said file-back having a horizontal slot extended completely across the same; an element slidable on the bottom wall and having members extending upwardly at opposite side edges of the file-back and each having a camming surface on the upper edge thereof; means for pivotally attaching said members to the file-back; other slidable mem- 70 bers to the file-back; other slidable mem- 75

bers vertically aligned with the first mentioned members and arranged to engage said abutments and each having a camming surface on the lower edge thereof for cooperation with the first mentioned camming surfaces; and means for pivotally attaching said other slidable members to the file-back, said attaching means including a plurality of horizontal pins extending through

the slot and each projecting on opposite sides of the vertical side edges of the file-back, the first mentioned members being pivotally associated with one of the pins and the said other members being pivotally associated with the other ⁵ pin.
